UNITED STATES PATENT OFFICE.

EMERY GUAY, OF SPOKANE, WASHINGTON.

SAW-SET.

1,375,147.

Specification of Letters Patent. Patented Apr. 19, 1921.

Application filed November 29, 1919. Serial No. 341,479.

To all whom it may concern:

Be it known that I, EMERY GUAY, a citizen of the United States, and residing at Spokane, in the county of Spokane and

5 State of Washington, have invented a new and useful Saw-Set, of which the following is a specification.

The object of my invention is to provide an instrument adapted for use in correctly 10 setting the teeth of saws without requiring the use of a spider or rectifying gage of any kind; and to provide an instrument adapted for using three different sets to cover all makes of saws; and to provide simple and 15 convenient means for adjusting the device. I attain the objects of my invention by the mechanism illustrated in the accompanying drawings, in which—

Figure 1 is a side elevation of the invention, with a portion broken away to show 20 opening 15;

Fig. 2 is a view of the invention, partly in section and partly in elevation, the portion in section being a section on the line 2—2 25 of Fig. 3;

Fig. 3 is a rear elevation; and

Fig. 4 is a transverse section on the line 4—4 of Fig. 1.

Like numerals designate like parts in each 30 of the views.

Referring to the accompanying drawings, I provide a suitable handle 1 terminating in a bottom jaw 2, on which is adjustably mounted a movable anvil plate 13, adapted 35 to be set forward or back by means of screws 14 which extend through oblong openings 15, the heads of the screws being wider than said openings, as indicated in Fig. 3. I further provide an adjusting screw 16 and 40 a suitable washer 17 for raising or lowering the setting block or anvil plate 13. I further provide a setting pin 8 mounted at the angle shown in the accompanying drawings in the extension or head 3, and normally held 45 in retracted position by a suitable spring 11. I further provide a suitable cotter pin 10 mounted in setting pin 8, and adapted to seat in slot 12 in head 3 when setting pin 8 is in retracted position, as shown in Fig. 2. Setting pin 8 is provided with a rounded end 50. Setting block 13 is provided with a rounded portion 18 as illustrated in the drawings. I provide a sight opening 9 through which the rounded end of setting 55 pin 8 may be viewed when the device is in operation. 19 designates the front surfaces

of the members 20 which connect head 3 with handle 1. Pin 8 is slidable in passage 6 in head 3; and is provided with a suitable head 7 against which spring 11 presses. I 60 provide a suitable overhanging lip 4 on head 3, as illustrated.

In use the device is operated by placing the set over the saw tooth and pushing or holding against the saw while striking the 65 setting pin with a light hammer. The rounded end of the setting pin will strike all teeth of the saw in exactly the same place and will positively set every tooth alike without using a spider or rectifying gage 70 of any kind. By providing the means for adjusting the setting block or anvil plate illustrated, that member may be adjusted to suit the instrument to different kinds of saws or where it is desired to give more or 75 less set to the teeth of the saw. By loosening the side screws 14 the setting block 13 may be moved downward, the screw 16 first being loosened and the device adjusted to any gage or set desired, the side screws 14 80 then being tightened, and the setting block being held in the desired position by the gage screw 16 or its washer 17. When once adjusted the device will set the saw perfectly according to the gage to which it is 85 adjusted; for example, it will require a smaller set for a hand saw, buck saw or small band saw, and one of larger size for sawmill band saw. It is within the contemplation of my invention to provide different sets to cover all makes of saws. 90

What I claim is:

1. In a device of the class described, the combination of a handle having an extension head, arms connecting the handle with 95 said head and having a sight opening positioned beneath the head, a setting pin slidably mounted in the head and having a rounded end, a spring normally retaining the pin in retracted position, and a transverse smaller pin mounted in the setting pin adapted to limit its retracted movement, a setting block having a rounded portion, means for longitudinally adjusting and setting said block, and means for holding said block in its longitudinally adjusted position in the handle, whereby the device is adapted for setting the teeth of different types of saws. 100

2. In a device of the class described, the 110 combination of a handle having an extension head, arms connecting the handle with

said head and having a sight opening positioned beneath the head, a setting pin slidably mounted in the head and having a rounded end, a spring normally retaining the pin in retracted position, and a transverse small pin mounted in the setting pin adapted to limit its retracted movement, a setting block having a rounded portion, and means for setting and adjusting said block, 10 said means comprising a bottom jaw having

opposite oblong slots, screws adjustably positioned in said slots and engaging the setting block, the heads of the screws extending beyond the block, and a gage screw and washer engaging the forward edge of the setting block and adjustably securing same in the desired adjusted position, whereby the device is adapted for setting the teeth of different types of saws. 15

EMERY GUAY.
